CABINET FOR TELEPRINTER OR THE LIKE

Berndt Ebbe Frick, 9 Herrgårdsvägen,
13500 Tyresö, Sweden

Filed Dec. 22, 1971, Ser. No. 211,169

Claims priority, application Sweden June 23, 1971

Term of patent 14 years

Int. Cl. D18—01

U.S. Cl. D64—11 R

Fig. 1

Fig. 2

FIG. 1 is a top perspective view of a cabinet for teleprinter or the like, showing my new design; and
FIG. 2 is a bottom perspective view thereof.

The left side of the cabinet presents a similar appearance to that of the right side shown in FIG. 1.

I claim:

The ornamental design for a cabinet for teleprinter or the like, substantially as shown and described.
